UNITED STATES PATENT OFFICE.

ATHERTON D. CONVERSE, OF WINCHENDON, MASSACHUSETTS.

DRUM.

1,209,675.

Specification of Letters Patent. Patented Dec. 26, 1916.

Application filed June 1, 1915. Serial No. 32,010.

To all whom it may concern:

Be it known that I, ATHERTON D. CONVERSE, a citizen of the United States of America, and a resident of Winchendon, in the county of Worcester and Commonwealth of Massachusetts, have invented certain new and useful Improvements in Drums, of which the following is a specification.

10 The present invention relates to toy drums, and has for its object the provision of means for ornamenting the exterior of the shell whereby the general appearance of the periphery of the body of the drum may 15 be changed at will.

The invention consists of surrounding the shell of the drum with a plurality of rings each having a plurality of characters thereon, each ring being adapted to be 20 moved independently of the other rings to cause the characters thereon to coact with selected characters on the other rings, thereby forming a puzzle which makes the drum additionally attractive to the owner as 25 it may be used for two distinct purposes.

The invention further consists in certain novel features of construction and arrangement of parts which will be fully understood by reference to the description of the 30 drawings and to the claims hereinafter given.

Of the drawings: Figure 1 represents an elevation of a drum embodying the principles of the present invention, and Fig. 2 35 represents a vertical section of the same.

Similar characters designate like parts throughout the figures of the drawings.

In the drawings, 10 is the cylindrical shell or body of a drum having secured to 40 the ends thereof the heads 11 and 12. The shell 10 is of greater diameter at each end to receive the heads 11 and 12, thereby forming shoulders 13 and 14 between which are interposed rings 15, 16, and 17, each of 45 which is U-shaped in cross section. The flanges of the rings 15, 16, and 17 bear against the periphery of the shell 10, thus reducing the friction to a minimum when the ring is moved about the axis of said shell or body 10. The drum is provided with the usual cords 18 and tightening straps 19. Each of the rings 15, 16, and 17 is provided with a plurality of compartments 20 and each compartment 20 is 50 provided with a character of some description such as a letter 21 of the alphabet or a sec-

tion 22 of a picture. As shown in the drawings the ring 15 has a series of heads in alternate compartments 20 thereon, while the ring 16 is provided with a series of 60 bodies 23 and the ring 17 with a series of legs 24. Each ring 15, 16, or 17, is provided with a plurality of perforations 25 by which the rings may be moved relatively to each other, a pencil or other similar 65 member being inserted in a perforation for this object.

A child when tired of drumming may amuse itself by changing the positions of the various rings and making various combinations of heads, bodies, and legs, the combinations thus effected in some cases being very hideous. The combination of the letters on the various rings will spell various words and consequently the drum 75 may be used for instruction.

While individuals of different races are shown on the rings in the drawings, it is evident that the pictures of well-known persons may be substituted therefor, or the 80 compartments may be supplied with sections of interior or exterior views.

The device may be used as a puzzle for the smaller children by moving the rings 15, 16, and 17 about the axis of the shell so 85 as to mix up the various compartments and then let a child endeavor to reset the rings in their proper positions.

It is obvious that drums thus constructed will afford additional attraction to small 90 children and would have the additional advantage that a child's attention would be diverted a portion of the time from beating the drum while he is amusing himself with changing the various characters on the 95 periphery of the shell.

It is believed that the operation and many advantages of this invention will be 100 fully understood from the foregoing description.

Having thus described my invention, I claim:

1. In a toy puzzle drum, the combination of a cylindrical shell having enlarged end portions; a sounding head set into each end portion; and a plurality of abutting rings independently movable around the periphery of said shell, each ring being provided with a plurality of characters adapted to register with the characters on the other rings and all of which are continuously exposed to view. 110

2. In a toy puzzle drum, the combination of a cylindrical shell having end portions extending outwardly beyond the intermediate portion; a sounding head set into each end portion; a plurality of independently movable rings surrounding said shell between said heads, each ring being U-shaped in cross section; and a plurality of characters on said rings adapted to coat with each other with the tops and bottoms of said characters adjacent the edges of said rings.
3. In a toy puzzle drum, the combination of a cylindrical member having end portions extending outwardly beyond the intermediate portion; a sounding head set

into each end portion; a plurality of rings surrounding said member between said shoulders and having their outer faces continuously exposed to view; a plurality of characters on said exposed faces with their tops and bottoms adjacent the edges of said rings; and means whereby each ring may be moved about the axis of said cylindrical member.

25
Signed by me at 4 Post Office Sq., Boston, Mass., this 20th day of May, 1915.

AATHERTON D. CONVERSE.
